FRACTURE CLAMP

Robert S. Rickard, Alliance, Ohio

Application June 11, 1952, Serial No. 292,890

5 Claims. (Cl. 128—83)

The invention relates to means for holding a bone fracture in reduced position, and more particularly to an improved clamp having resilient means for applying the desired amount of pressure to the fracture.

It is an object of the invention to provide a clamp having a spring loaded pressure plate adapted to be incorporated in a movable portion of the cast covering the fracture.

Another object is to provide a cylinder having a spring loaded piston therein for adjusting the pressure plate.

A further object is to provide a supporting bracket for said cylinder adapted to be permanently incorporated in the cast covering the fracture.

A still further object is to provide such a device in which the supporting bracket is in the form of a C-clamp adapted to be attached to the cast at the opposite side to the pressure plate.

The above objects together with others which will be apparent from the drawings and following description, or which may be later referred to, may be attained by constructing the improved fracture clamp in the manner hereinafter described in detail and illustrated in the accompanying drawings, in which:

Fig. 1 is a plan view of a fracture clamp embodying the invention;

Fig. 2 an enlarged longitudinal, sectional view through the cylinder and spring loaded piston, showing a portion of the support bracket upon which the cylinder is mounted;

Fig. 3 a detached side elevation of the piston;

Fig. 4 a longitudinal, sectional view of the pressure plate;

Fig. 5 a transverse section through the shank of the pressure plate, showing the spring clip for detachably connecting the pressure plate to the adjusting screw of the piston, taken on the line 5—5, Fig. 4;

Fig. 6 a perspective view of a modified form of support bracket with the cylinder attached thereto;

Fig. 7 a side elevation of an ankle with cast thereon, showing the improved fracture clamp applied thereto;

Fig. 8 a rear elevation of the ankle, showing the cast and fracture clamp in section;

Fig. 9 a transverse section taken as on the line 9—9, Fig. 8;

Fig. 10 a transverse section through a knee joint with cast thereon, showing the modified form of fracture clamp applied thereto; and,

Fig. 11 a diagram of a chart showing spring pressure obtained by adjustment of the piston.

Referring now to the embodiments of the invention illustrated in the drawings, the improved fracture clamp to which the improvements pertain comprises a cylinder 11, the wall thickness of which may be increased at its inner end, as indicated at 12, to receive attaching screws 13, for connecting the cylinder to the C-shape support bracket 14 shown in Figs. 1, 2, 7, 8 and 9, through the bayonet type or key hole slots 13a shown in Fig. 2, or to

2

the flat support bracket 15, with angular extensions 16, shown in Figs. 6 and 10.

Slidably located within the cylinder 11 is a piston 17, having a radial stud 18 engaged in the longitudinal slot 5 19 in the cylinder bore, to prevent relative rotation of the piston within the cylinder.

The cylinder bore is internally threaded as shown at 20, to receive the externally threaded pressure adjusting disc 21. This disc may be provided with diametrically opposed sockets or apertures 22, to receive a conventional form of wrench for rotating the disc within the threaded cylinder bore, and has the central opening 23 to receive the hollow shank or piston rod 24, of the piston 17.

The outer side of the piston is shouldered at 25, to receive the coil spring 26, which is located within the cylinder bore and interposed between the piston and the pressure adjusting disc 21.

A spiral groove or marking 27, of the same pitch as the screw threads 20, is formed upon the exterior of the tubular piston rod 24. An arrow 28 is radially located upon the outer surface of the pressure regulating disc 21 for cooperation with the graduations 29 upon the outer end of the cylinder 11.

The piston 17 is internally threaded as shown at 30, to receive the space adjustment screw 31, which has a ball 32 formed at its inner end, and may have a hexagonal socket 33 in its outer end, to receive an Allen-head screw driver for adjusting the screw relative to the piston. In cases where considerable adjustment may be required, the screw 31 may be of greater length, as indicated in Fig. 6.

The pressure plate may be in the form of a disc 34, which may be concaved on its inner side, as shown at 35, and has the central boss 36 at its other side, having a socket 37 therein to receive the ball 32 upon the space adjustment screw 31.

A peripheral groove 38 is formed in the boss 36 and transverse slots 39 extend from said groove into opposite sides of the socket 37, for receiving a U-shape or hairpin spring 40, for engaging behind the head 32 of the space adjustment screw and detachably holding the pressure plate upon the screw.

As shown in Figs. 1, 2, 7, 8 and 9, the cylinder 11 may be attached to one end of the C-shape support bracket 14, for use as upon an ankle fracture, as shown in Figs. 7, 8 and 9.

In the application of the improved fracture clamp for such use, the procedure is to first set the fractured joint, and then wrap the joint with cotton as indicated at 41. A plaster cast or bandage 42 is then molded on the outer side of the joint, as a pressure surface at the desired region, the pressure plate 34 being embedded or molded into said cast.

Then a second wrapping of cotton, shown at 43, is wrapped around the joint and over the cast 42, containing the pressure plate 34, so that this cast, with the pressure plate therein, may be floating between the cotton wrappings 41 and 43.

A light plaster cast 44 is then applied entirely around the joint, over the cotton wrapping 43, leaving a small opening 45 over the socket in the pressure plate 34. The joint may then be X-rayed to see that it is properly set. It should then be determined that the pressure cast 42, with the pressure plate therein, floats freely between the cotton wrappings 41 and 43, by pressing lightly with the fingers upon the pressure plate 34, through the small opening 45 in the light plaster cast 44, after which the C-shape support bracket 14 is positioned around the joint, as shown in Figs. 7, 8 and 9, and the head 32 of the space adjustment screw is inserted into the socket 37 of the pressure plate.

With the C-shape bracket 14 held in proper position, a plaster cast or bandage 46 is then placed around the joint, and around the bracket 14 and the cast is allowed to dry.

Then set the pressure adjusting disc 21 at 0, and back off the space adjustment screw 31. Then tighten the space adjustment screw until the piston 17 starts to actuate, after which back off the space adjustment screw one-half turn to assure that no continual pressure is upon the skin surrounding the fracture.

Then set the pressure adjusting disc 21 to the desired starting spring pressure, which starting pressure may be obtained from the chart shown in Fig. 11.

For treatment of the fracture, first determine the maximum pressure to be applied to the joint, then set the spring pressure adjusting disc 21 to a starting spring pressure slightly under the maximum pressure and tighten the space adjustment screw until the piston starts to actuate.

The spiral scale 27 on the piston shank is observed to assure that the maximum pressure is not exceeded as more pressure is applied by the space adjustment screw. The joint is now reset but under continual pressure.

Then back off the spring pressure adjusting disc 21 until the same is flush with the housing and set at 0, and loosen the space adjustment screw until the piston is fully retracted, after which the screw is loosened another half turn to assure that there is no continual pressure on the skin. After this the pressure adjusting disc 21 is set to the desired starting spring pressure which may be obtained from the chart shown in Fig. 11.

In applying the improved fracture clamp to a knee joint or the like, where it may not be convenient to use the C-shape bracket 14, the flat bracket 15, as shown in Figs. 6 and 10, may be used.

In the application of this form of the clamp to the fractured joint, a cotton wrapping 41a is first applied around the joint, after which the plaster pressure mold 42a, with the pressure plate 34 embedded therein, is molded around the cotton at the proper point and a second cotton wrapping 43a is placed around the same, as in Figs. 8 and 9, after which a plaster cast 47 is placed entirely around the joint with the bracket 15 embedded therein and the procedure is otherwise as above described with reference to Figs. 7, 8 and 9.

With this form of supporting bracket shown in Figs. 6 and 10, it will be obvious that the bracket may be located in the plaster cast at any desired angle to apply pressure in the right direction to the joint.

In the foregoing description, certain terms have been used for brevity, clearness and understanding, but no unnecessary limitations are to be implied therefrom beyond the requirements of the prior art, because such words are used for descriptive purposes herein and are intended to be broadly construed.

Moreover, the embodiments of the improved construction illustrated and described herein are by way of example, and the scope of the present invention is not limited to the exact details of construction.

Having now described the invention or discovery, the construction, the operation, and use of preferred embodiments thereof, and the advantageous new and useful results obtained thereby; the new and useful constructions, and reasonable mechanical equivalents thereof obvious to those skilled in the art, are set forth in the appended claims.

I claim:

1. A fracture clamp comprising a support bracket, a cylinder mounted upon said bracket, a piston within said cylinder, a spring in the cylinder contacting the piston,

the cylinder being internally threaded throughout a substantial portion of its length, a pressure adjusting disc threaded into the cylinder for adjusting the spring pressure upon the piston, a space adjustment screw in the piston and a pressure plate connected to the screw.

2. A fracture clamp comprising a support bracket, a cylinder mounted upon said bracket, a piston within said cylinder, a spring in the cylinder contacting the piston, the cylinder being internally threaded throughout a substantial portion of its length, a pressure adjusting disc threaded into the cylinder for adjusting the spring pressure upon the piston, a pressure plate connected to the piston, a dial upon the outer end of the cylinder and an indicator on the pressure adjusting disc cooperating with said dial.

3. A fracture clamp comprising a C-shape support bracket adapted to surround a fractured joint, one end of the bracket being adapted to be located on one side of the joint, a cylinder mounted upon the other end of the bracket diametrically opposite to the first-named end of said bracket, a piston within said cylinder, a spring in the cylinder contacting the piston, the cylinder being internally threaded throughout a substantial portion of its length, a pressure adjusting disc threaded into the cylinder for adjusting the spring pressure upon the piston, a pressure plate connected to the piston, a dial upon the outer end of the cylinder and an indicator on the pressure adjusting disc cooperating with said dial.

4. In combination, a plaster pressure cast surrounding a portion of a joint containing fractured bone parts, a pressure plate embedded in said pressure cast, a cylinder, a spring loaded piston in the cylinder, the cylinder being internally threaded throughout a substantial portion of its length, a pressure adjusting disc threaded into the cylinder for adjusting the spring pressure upon the piston, means connecting the piston to the pressure plate, a support bracket attached to the cylinder, a second plaster cast surrounding the joint and the pressure cast, the support bracket being embedded in said second plaster cast, and a layer of resilient material between the pressure cast and the second plaster cast.

5. In combination, a plaster pressure cast surrounding a portion of a joint containing fractured bone parts, a pressure plate embedded in said pressure cast, a cylinder, a spring loaded piston in the cylinder, the cylinder being internally threaded throughout a substantial portion of its length, a pressure adjusting disc threaded into the cylinder for adjusting the spring pressure upon the piston, ball and socket means providing a universal joint detachably connecting the piston to the pressure plate, a support bracket attached to the cylinder, a second plaster cast surrounding the joint and the pressure cast, the support bracket being embedded in said second plaster cast surrounding the joint and the pressure cast, the support bracket being embedded in said second plaster cast, and a layer of resilient material between the pressure cast and the second plaster cast.
